UNITED STATES PATENT OFFICE.

CHARLES F. CRANDALL, OF ILION, NEW YORK.

HANGER FOR TYPE-WRITER TYPE-BARS.

No. 882,627.

Specification of Letters Patent. Patented March 24, 1908.

Application filed July 15, 1907. Serial No. 383,881.

REISSUED

To all whom it may concern:

Be it known that I, CHARLES F. CRANDALL, of Ilion, in the county of Herkimer and State of New York, have invented certain new and useful Improvements in Adjustable Hangers for Type-Writer Type-Bars; and I do hereby declare that the following is a full, clear, and exact description thereof, which will enable others skilled in the art to which it appertains to make and use the same, reference being had to the accompanying drawings, and to the letters of reference marked thereon, which form part of this specification.

The object of my invention is to provide an improved hanger for the type lever or bar of a typewriter whereby the type bar may be conveniently adjusted to its bearings and the arm adjusted relative to the paper roll or platen and the whole removed or replaced with facility.

Figure 1 shows a type bar hanger of my improved construction shown in its relative relation to other coöperative parts of what is ordinarily termed a visible writer in a diagrammatical manner. Fig. 2 is an enlarged detail of the hanger, together with portions of the type bar and frame, the latter shown in section. Fig. 3 is a plan view of the part shown in Fig. 2. Fig. 4 is an inside view of one of the walls or parts of the hanger. Fig. 5 is a side elevation, and Fig. 6 is a plan view of what may be termed the base end or part of the hanger. Fig. 7 is a detail view showing the pivotal end of the type bar. Fig. 8. 35 is a sectional view of a modified form of construction of hanger and mountings. Fig. 9 is an inside face view of one of the main parts of the form of construction shown in Fig. 8.

Referring to the reference letters and figures in a more particular description, 5 indicates the type bar carrying the ordinary double-faced type 6 and pivoted at 7 and arranged in such manner as to strike the paper roll or platen 8. For operating the type bar there is provided a bell crank lever 9 connected by adjustable connecting rod 10 with the short arm of the type bar. The lever 9 is pivotally mounted in any suitable fixed support or bearing as 11, and is connected by a connecting rod 12 with a key lever 13. 14 indicates a spring for lifting the key lever and assisting in returning the type bar to its normal position. 15 indicates a pad on which the end of the type bar is adapted to rest in its normal position. The particular details of all these parts is not material as my im-

provements hereinafter described are equally useful on that class of typewriters in which the type bars normally are in a suspended position and strike inwardly and upwardly. 60

A support for the type bar hangers is shown in the frame bar 16, which has a semi-spherical socket 17, there being as many sockets 17 provided as are required for mounting the desired number of type bars. 65 The hanger 18 consists of two main side walls 18^a spaced apart to receive the pivotal end of the type bar and secured to the hanger base piece 18^b conveniently by a pair of rivets *a* as shown. The piece 18^b is provided with a semispherical bearing end 18^c, which is received in and fits snugly in the socket 17 in the frame bar. For securing the hanger to the frame bar there is provided a bolt 19, which passes through the bar 16, passing in part through the socket 17 and in part through a hole perforating the balance of the bar. The bolt 19 is loosely connected to the part 18^b by entering a socket provided in the end of the base part 18^b and being secured 70 therein by a pin 20. On the rear side of the frame bar 16 the bolt will be provided with a nut 21 and preferably with a washer as shown. The pivotal end of the type bar 5 is provided with conical bearing projections 85 5^a, which fit conical bearing openings in the walls of the hanger. Extending between the walls of the hanger and threaded into each is a screw 25 having right and left hand threads 90 engaging in said walls respectively, and provided centrally with an angular enlargement or boss 25^a adapted to receive a wrench. By rotating the screw 25 in one direction or the other the walls 18^a may be closed together or sprung apart whereby the type bar 5 may be 95 very nicely and accurately adjusted in its bearings, which as well known is very important in a typewriter at this point. When the nut 21 securing the hanger 16 is loosened the hanger may be adjusted to a limited amount 100 in any direction whereby the position of the type with reference to the platen may be changed to the desired position. When so adjusted the hanger will be firmly secured in its desired position by tightening the nut 21. 105

In the construction of hanger shown in Figs. 1 to 6 inclusive, it is required that the pivotal end of the type bar be inserted in place between the plates 18^a before the several parts of the hanger are secured together. 110 In the form of construction shown in Figs. 8 and 9 this is obviated by forming the hanger

in two parts 27, 28. These parts include the semispherical bearing part *b*, which engages in the socket in the frame bar. For the purpose of securing the hanger in the socket there is provided a bolt having a semispherical head 29 engaging in a semispherical socket 30 provided partially in one part 28 and partially in the other part 27. The semispherical head part of this hanger is adapted to be received in a semispherical recess in the frame bar 16 as of the previously described construction, and the same is adapted to be held and firmly clamped in any desired position by the bolt. It will be noted with reference to this construction that when removed from the socket it can be entirely taken down by removing the screw 25.

It is evident that other modifications and changes in and from the construction herein described may be made without departing from the spirit of my invention.

What I claim as new and desire to secure by Letters Patent is:

1. A hanger for a type bar having substantially semispherical bearing, a frame bar having socket to receive the bearing and a bolt engaging in the hanger and passing

through the socket and the bar and arranged to bind the hanger to the bar, substantially as set forth:

2. A hanger for a type bar having substantially semispherical bearing, a frame bar having a socket to receive the bearing, a bolt movably engaging the hanger and passing through the socket and frame bar, substantially as set forth.

3. A hanger for a type bar having spaced walls and a substantially semispherical bearing, a type bar mounted between said walls and having bearing pivots engaging in the walls, a frame bar having a socket to receive the bearing, means for binding the hanger to the frame bar with the semispherical bearing engaging in the socket and means for adjusting said side walls toward and from each other to adjust the bearings of the type bar in the hanger, substantially as set forth.

In witness whereof, I have affixed my signature, in presence of two witnesses, this 6th day of July 1907.

CHARLES F. CRANDALL.
